J. C. SHAMBOW,

SHUTTLE,

APPLICATION FILED JUNE 30, 1920.

Patented Feb. 15, 1921.

Inventor
John C. Shambow
By Joseph A. Miller
Attorney

UNITED STATES PATENT OFFICE.

JOHN C. SHAMBOW, OF WOONSOCKET, RHODE ISLAND, ASSIGNOR TO SHAMBOW SHUTTLE COMPANY, OF WOONSOCKET, RHODE ISLAND, A CORPORATION.

SHUTTLE.

1,368,975.

Specification of Letters Patent. Patented Feb. 15, 1921.

Application filed June 30, 1920. Serial No. 393,136.

To all whom it may concern:

Be it known that I, JOHN C. SHAMBOW, a citizen of the United States, residing at Woonsocket, in the county of Providence and State of Rhode Island, have invented 5 new and useful Improvements in Shuttles, of which the following is a specification.

This invention relates to certain new and useful improvements in shuttles and the primary object of the invention is to provide 10 the shuttle with means so as to improve the wearing properties thereof, and accordingly the invention resides in providing either the top or bottom surface, or both, of the shuttle 15 with strips or pieces or plates of fiber, rigidly secured to the shuttle so as to form practically an integral part thereof.

The invention further aims to provide simple, economical and effective means for 20 securing the fiber in position on the shuttle, and to also secure the ends of the fiber so that same cannot move away from the shuttle.

Further and other objects will be later set 25 forth and of themselves manifested in the course of the following description.

In the drawings:

Figure 1, is a top plan view of a shuttle equipped with the present invention:

30 Fig. 2 is a section on line 2-2 of Fig. 1; and

Fig. 3 is a similar though fragmentary sectional view of a modified form of the invention.

35 In proceeding in accordance with the present invention the shuttle body S is formed with a series of holes 2 into which dowel pins 3 are secured at one end. The opposite ends of the dowel pins project beyond the 40 surface of the shuttle and into holes 4 formed in the under surface of the fiber pieces or plates 5. As depicted in the drawings the holes 4 do not extend completely through the fiber plate, but only extend 45 through the inner faces thereof, so as to leave the outer surfaces of the fiber plate smooth and uninterrupted. In applying the plates in position cement is employed which is placed around the dowel pins and in all of 50 the holes and also between the inner surfaces of the fiber pieces and the shuttle faces.

For the purpose of securing the ends of the fiber pieces in position and against all movements, same are shouldered at 6 by reducing the ends of the fiber, which shoulders are overlapped by tongues 7 formed by

undercutting the inner walls of the usual metallic points, tips or end pieces 8 which are applied to the shuttle ends.

As depicted in Fig. 3, the fiber ends may 60 be tapered or beveled as indicated at 9 and the metallic end piece 8' is provided with a corresponding tapered or inclined tongue 10, which overlaps the tapered end 9 of the fiber piece.

65 It will be understood that the holes 4 formed in the fiber pieces are predeterminedly spaced so as to correspond to the spacing of the pins 3 borne by the shuttle, so that the fiber can first have the glue applied 70 thereto and then be applied to the pins and forced thereover and into engagement with the shuttle faces. The end pieces 8 and 8' of the shuttle are then secured in position 75 so as to in each instance overlap the reduced ends of the fiber, whereby the latter will be held in position and at the same time the metallic end pieces will form a flush joint with the fiber so as to not leave any projection likely to catch or obstruct the shuttle 80 movements. Obviously the fiber is cut away where necessary in order to expose the shuttle interior and to conform to the normal upper and lower faces of the shuttle body.

85 Having thus described my invention what I claim as new and desire to secure by Letters Patent is:—

1. In a shuttle, a body having pins projecting from a face thereof, a fiber wearing 90 plate having holes extending through its inner face and predeterminedly spaced to receive the pins, the outer face of the wearing plate being smooth, said plate having its ends reduced in thickness, and metal end 95 tips for the body having reduced parts which overlap the reduced ends of the plate and lie flush with the outer surface of the plate.

2. In a shuttle, pins projecting from a 100 face of the shuttle, a fiber plate having holes extending part way therein to receive the pins, metal end tips for the shuttle, and means whereby said tips hold the plate ends against movement.

105 In testimony whereof I have signed my name to this specification in the presence of two subscribing witnesses.

JOHN C. SHAMBOW.

Witnesses:

E. P. TOOMEY,
J. A. MILLER.
